R. T. TAYLOR

COLLAPSIBLE FORM

Filed May 7, 1923

UNITED STATES PATENT OFFICE.

RALPH T. TAYLOR, OF PASADENA, CALIFORNIA, ASSIGNOR TO W. A. TAYLOR & SONS, OF PASADENA, CALIFORNIA, A PARTNERSHIP COMPOSED OF W. A. TAYLOR, REA P. TAYLOR, AND RALPH T. TAYLOR.

COLLAPSIBLE FORM.

Application filed May 7, 1923. Serial No. 637,281.

To all whom it may concern:

Be it known that I, RALPH T. TAYLOR, a citizen of the United States, residing at Pasadena, in the county of Los Angeles and State 5 of California, have invented certain new and useful Improvements in Collapsible Forms, of which the following is a specification.

This invention relates to collapsible forms used for coring out of air spaces in hollow 10 concrete walls and other molded blocks or structures.

The present invention has for its object 15 the provision of an improved collapsible core which can be quickly and easily expanded or set up and, also, readily collapsed, embodying a construction wherein setting up and collapsing are accomplished by positively acting mechanical means so that the form is rigid when expanded and also adapted to 20 be collapsed without difficulty after the concrete has set.

The invention comprises sides, ends adapted to cooperate with the sides with a wedging 25 action, means for limiting the relative expansion of the sides and with which the ends are adapted to cooperate, when collapsing is being effected, to positively draw the sides toward each other, and means for 30 positively relatively expanding, or contracting, the ends; thus, in my construction, whether the form is undergoing expansion or contraction, the action is a positive mechanical one which insures accomplishment of the foregoing object.

35 The operative action between the sides preferably comprises chains which limit the relative expansion of the sides and are also so positioned that they are engageable by the ends when the latter are contracted.

40 Preferably, the operating connection between the ends comprises a toggle joint which, when expanded, moves the ends into wedging relationship to the sides and, when "broken," draws the ends toward each other 45 and causes them to cooperate with the chains to thereby draw the sides toward each other.

The invention also embodies detail features having to do with the construction of the sides and ends and the support and oper-

ation of the chains, set forth more fully 50 hereinafter.

In the accompanying drawings:

Figure 1 is a vertical longitudinal section through the form when extended;

Fig. 2 is a horizontal section on the line 55 2-2, Fig. 1;

Fig. 3 is a vertical section on the line 3-3, Fig. 1;

Fig. 4 is a detail plan view of one corner of the form, certain parts being omitted; 60 and

Figs. 5 and 6 detail side and plan views, respectively, of a modified toggle strut.

The sides 1 are preferably of sheet metal reinforced by channel irons 2 to afford the 65 requisite stiffness. The ends 3 are preferably of wood and are of wedge shape as shown in Figs. 2 and 4. The ends of the sides 1 are bent or beveled at 4 to facilitate withdrawal of the form after collapsing. The formation 70 of the ends of the sides 1 may alone be relied upon for cooperation with the inclined or beveled parts of the ends 3 but I prefer to provide wooden strips 5, suitably secured to the sides 1 which have inclined faces bearing 75 upon the inclined faces of the ends 3. Filling strips, such as shown at 5, reinforce the ends of the sides 1 and afford suitable bearing surfaces for the ends 3 so that a firm and even contact may be obtained when the 80 ends 3 are wedged into position as shown in the drawings. Members 9 carried by the strips 5, engage the upper and lower extremities of the ends 3 for the purpose of preventing relative up and down movement of the 85 ends 3 and sides 1.

To prevent the ends 3 from twisting in relation to the sides 1, said ends are provided with plates or strips 10 which bear against the inner faces of the strips 5. 90

Chains or other suitable flexible connections 11 are secured to the sides 1 and are of such length that when the ends 3 are suitably wedged against the strips 5, the chains will be taut, thus limiting the relative expansion of the sides 1. The chains 11 are disposed sufficiently close to the ends 3 so that when the ends 3 are relatively contract- 95

ed by "breaking" the toggle strut 6, the ends 3 will engage said chains and positively pull the sides 1 toward each other, thus freeing them from the concrete which has been mold-
5 ed or poured.

To enable the ends 3 to be moved toward each other a suitable distance to permit freeing them from the molded or poured concrete and also to provide for suitable relative movement of the sides during this operation, the ends 3 are provided with channels or grooves 12 into which the chains may pass.

The chains 11 run through staples 13 carried by the ends 3 and are thereby prevented 15 from falling.

The different views of the drawing show the form expanded or set up ready for positioning in a mold into which concrete is to be poured. After the concrete has become set, 20 the toggle strut 6 is pulled upwardly by hand, thereby drawing the ends 3 toward each other and freeing them from the concrete. The engagement of the ends 3 with the chains 11 causes the sides 1 to be positively drawn toward each other, thus freeing them from the concrete. The form, having 25 been collapsed, can be readily withdrawn.

To set up the form, it is only necessary to 30 push down on the toggle strut 6 to bring it to the position shown in the drawings. This action forces the ends 3 against the strips 5 (or against the ends of the sides 1 if the strips 5 are not used) and expands the sides 1 in relation to each other until arrested by 35 the chains 11 becoming taut.

I am aware that jointed links might be substituted for the chains 11 and by the use 40 of the expression "flexible connections" in the claims, I intend to cover either jointed links, chains, wire cables, or any other flexible connections.

I am also aware that a toggle strut of different design might be substituted for the 45 toggle strut 6. This may be of any design embodying a hinged or pivoted connection joining the two component parts of the toggle in such a way as to secure a straightening and a breaking action or a toggle action, thus providing a simple and positive method 50 of moving the ends relatively toward or away from each other. This toggle may be of metal, wood, or other suitable material and may be secured to the ends 3, by any convenient method allowing toggle action.

55 In Figs. 5 and 6 I have shown a modified toggle strut composed of metal sections 6', 6" hinged to the ends 3 at 7' and operable by a handle 14 connected to section 6' and serving as a stop for the other section 6'',

as shown at 14'. By the expression "toggle 60 strut" I mean any mechanism embodying a toggle action for moving the ends relatively toward or away from each other.

I claim:

1. In a collapsible core, the combination 65 with relatively expansible and contractible sides, of relatively expansible and contractible ends adapted to cooperate therewith, flexible connections between the sides which are positioned for operation by the ends 70 when the latter are contracted, and means for expanding and contracting the ends.

2. In a collapsible core, the combination 75 with relatively expansible and contractible sides, of relatively expansible and contractible ends adapted to cooperate therewith, chains connecting the sides which are positioned for operation by the ends when the latter are contracted, and means for expanding and contracting the ends.

3. In a collapsible core, the combination 80 with relatively expansible and contractible sides provided with inclines or bevels at their ends, of wedge shaped ends adapted to cooperate with the inclines or bevels of the 85 sides, means for limiting the relative expansion of the sides, and a toggle strut connecting the ends by which said ends may be relatively expanded or contracted.

4. In a collapsible core, the combination 90 with relatively expansible and contractible sides provided with inclines or bevels at their ends, of wedge shaped ends adapted to cooperate with the inclines or bevels of the 95 sides, means for limiting the relative expansion of the sides, said means being arranged to be operated by the ends when the latter are relatively contracted, and a toggle strut connecting the ends by which said ends may be relatively expanded or contracted.

5. In a collapsible core, the combination 100 with sides adapted for movement toward and away from each other, of ends adapted for movement toward and away from each other and for engagement with the sides, 105 means for operating the ends as aforesaid, said ends having grooves or channels, chains connecting the sides to limit their relative expansion, and guides for said chains which are carried by the ends aforesaid, the chains 110 being disposed relatively to the ends so that when the ends are relatively contracted they will engage with the chains and cause contraction of the sides, the chains then passing into the grooves or channels aforesaid.

115 In testimony whereof I affix my signature.

RALPH T. TAYLOR.
